UNITED STATES PATENT OFFICE.

HENRY G. MUTSCHLER, OF ROCHESTER, NEW YORK, ASSIGNOR TO A. & H. G. MUTSCHLER, INC., A CORPORATION OF NEW YORK.

DOOR-CONTROLLING MEANS FOR ELEVATOR SHAFTS.

Application filed March 20, 1924. Serial No. 700,722.

To all whom it may concern:

Be it known that I, HENRY G. MUTSCHLER, a citizen of the United States, and resident of Rochester, in the county of Monroe and 5 State of New York, have invented certain new and useful Improvements in Door-Controlling Means for Elevator Shafts, of which the following is a specification.

The present invention relates to door controlling means for elevator shafts, and an object thereof is to provide a controlling means which is positive in action and durable in use, while, at the same time, being simple in construction. Another object of 15 the invention is to provide a door controlling means in which there is provided a detaining device for holding the door open and a locking device for preventing the complete opening of the door, both of such 20 devices being controlled by a common member which in turn is controlled by the elevator moving in the shaft. Another object of the invention is to provide a construction which will permit the door to open a small 25 amount when the car is away from the floor, which will permit the door to be opened from the outside or the inside when the car is at the floor, which will permit the door to be opened from the inside only when the 30 car is away from the floor, which will permit the door automatically to close and lock as the car leaves the floor and which will permit the door to be automatically detained in its open position without possibility of release when the car is at the 35 floor.

To these and other ends, the invention consists of certain parts and combinations of parts, all of which will be hereinafter 40 described; the novel features being pointed out in the appended claims.

In the drawings:

Fig. 1 is a fragmentary view of the shaft with the door in closed position and the 45 elevator in a position away from the floor;

Fig. 2 is a fragmentary view of the shaft showing the position of the locking device and detaining device when the door is closed and the elevator in position at the 50 floor; and

Fig. 3 is a perspective view of the door showing the abutments on the inner face thereof.

The elevator shaft of which only a fragment 55 1 is shown has a number of door open-

ings 2 adapted to be closed by doors 3 which have a normal tendency to move to closed position, this result, in this instance, being effective by mounting the doors to travel on inclined tracks 4. An elevator 5 moves up 60 and down in the shaft. Each door is provided on its inner face with an abutment block 6. The block 6 which is provided with an abutment 6^a has a bevelled face 6^b. The abutment 6^a of this block is adapted to be 65 engaged by a locking device to be herein-after more particularly described and is so situated that the door may be opened a few inches from the outside for the purpose of permitting one to reach into the elevator 70 shaft in order to operate the controlling rope of the elevator to bring the elevator to the floor without at the same time permitting the operation of the locking device.

The locking device, in this instance, is in 75 the form of a bell crank lever 8^a pivoted at 8 to that face of the door frame farthest removed from the vertical edge of the door adjacent the portion which opens first. One end of this bell crank lever cooperates with 80 the abutment block 6. When the locking device is in locking position and the door is open, this end of the locking lever 8 will cooperate with the bevelled face 6^b and shift the locking device on its pivot 8 as the door 85 moves to closed position so that the locking device will ride over the plate 6 until it passes behind the abutment 6^a.

Operation of the locking device may be effected by a controlling member in the form 90 of a lever pivoted at 9 and extending upwardly from its pivot being provided with two converging bevelled portions 10 and 11 on opposite sides of the straight portion 12, the bevelled portion 10 being below the floor 95 portion and the bevelled portion 11 being above the floor portion while the straight portion is opposite the floor. This lever at its upper end may be connected by a pin and slot connection 14 to a bell crank lever 100 8^a. As the elevator moves upwardly, it engages the bevelled portion 10 to move the lever inwardly and as the elevator moves downwardly, it engages the bevelled portion 11 to move the lever inwardly. The 105 straight portion 12 is engaged when the elevator is opposite the floor and holds the lever in its inward position. Outward movement of the lever may be effected by a spring 15 which is anchored at 16 to the door casing 110

and bears against the projection 17 on the lever. It is apparent that, after the lever moves inwardly, the lock is moved upwardly away from locking position and as 5 the lever moves outwardly, the lock is moved downwardly to locking position.

In order to hold the door in open position against closing, a locking device may be provided preferably in the form of a lever 10 18 pivoted at 19 to the controlling lever between its ends and having one end connected to a helical spring 20 which at 21 is connected to a fixed point on the door casing. This arrangement causes the detaining device 18 to lie out of detaining position when the controlling lever lies in its outermost position, but, when the controlling member is moved inwardly, the pivot 19 of this lever is shifted in such a way as 15 to place the spring 20 under tension and in this way throw the detaining end of the lever upwardly and toward the door into the path of an abutment 7^a on a plate 7 which is secured to the inner face of the door nearer that edge thereof which is the 20 first to open the door. This plate 7 is bevelled at 7^b so that the door may be opened after the detaining member is shifted to detaining position.

30 The operation of the invention will be understood from the foregoing but it may be summarized as follows: After the elevator 5 reaches the floor 3 from either direction it engages one of the bevelled portions 10 or 11 and thereafter rides on the straight portion 12. This moves the controlling member inwardly against the action of the spring 15 and shifts the locking member 8^a upwardly out of the path of the abutment 6^a so that the door is unlocked. At 35 the same time, the detaining member 18 is swung upwardly into the path of the plate 7. The door is then opened and the bevelled portion 7^b of the plate 7 cooperates with the detaining member 18 and shifts the latter until the abutment 7^a is passed, after which the detaining member swings in front of said abutment and holds the door in open position. Should it be desired to close the 40 door, while the elevator is at a floor, then the detaining member 18 is moved downwardly by hand to free the door and permit it to move under the action of gravity to closed position. Assuming, however, that 45 the door remains open until the elevator moves off the straight portion 12 in either direction, then the spring 15 will shift the controlling member, thus moving the detaining member 18 downwardly freeing the door to the action of gravity and at the 50 same time moving the locking member 8^a downwardly. The locking member yields under the action of bevel face 6^b as the door closes, and then springs in the path of the 55 abutment 6^a which when the door is closed 60 65

lies in spaced relation to the locking device so that the door may be opened a few inches in order that one may reach through the opening in order to grasp the controlling member or rope of the elevator.

From the foregoing it will be seen that there has been provided a construction which will permit the door of an elevator shaft to open a small amount when the car is away 75 from the floor for the purpose of controlling the elevator, while at the same time preventing the door opening an amount which would permit a person to pass into the elevator shaft. When the car is at the floor, the door can be opened. When the car is in any position the door may be opened from 80 the inside only provided pressure is applied to the controlling member 12. The door automatically closes and is locked as the car leaves the floor. When the car is at the floor, the door is automatically detained in 85 an open position but can be unlocked to close the door.

What I claim as my invention and desire to secure by Letters Patent is:

1. The combination with an elevator shaft having a door opening and a door for closing said opening having a tendency to move to closed position, of a detaining device for holding the door open, a locking device for preventing the complete opening of the door, and a common controlling means for the detaining device and the locking device controlled by an elevator movable in the shaft.

2. A door controlling means for an elevator shaft comprising a controlling member having two converging portions, one of which is engaged by an elevator when moved in one direction and the other of which is engaged by an elevator in moving in the other direction, a pivotally mounted locking member for holding the door against complete opening movement having a pin and slot connection with the free end of the controlling member, a spring acting on the controlling member to move the locking member to locking position, a detaining member for holding the door in open position, said detaining member being pivoted to the operating member, and a helical spring connected to the detaining member and to a fixed part.

3. Controlling means for elevator doors comprising a movable controlling member having two converging portions, one engaged by the elevator in moving in one direction and the other engaged by the elevator in moving in the other direction, a locking member controlled by said controlling member for holding the door against complete opening movement, and a detaining member controlled by said controlling member for holding the door in open position.

4. The combination with an elevator shaft having a door opening and a door for closing said opening having a normal tendency to move to closed position, of a locking means, a detaining means, a common controller for moving the locking means to unlocking position and the detaining means to detaining position and vice versa, and two abutments on the door, one situated to be engaged by the detaining means to hold the door open and the other situated in a position to be engaged by the locking means to permit a slight opening movement of the door while preventing a complete opening movement of the door, said controlling member being situated in such a position on the inner side of the door that it cannot be reached by a person by way of the opening provided when the door is locked against complete opening movement.
5. The combination with an elevator shaft having a door opening at a floor intersecting the shaft, and a door for closing said opening having a normal tendency to move to closed position, of a controlling member pivoted on the inner side of the door below the floor and extending upwardly above the floor, said controlling member having a straight portion opposite the floor and converging portions above and below the floor to be engaged by an elevator movable in the shaft to shift the controlling member on its pivot, a spring opposing the movement of said controlling member, a pivotally mounted locking member having a pin and slot connection with the upper end of the controlling member and moved out of lock-
- ing position when the controlling member is moved against the action of the spring, a detaining member pivoted to the controlling member, a spring secured to a fixed part and to said detaining member to be placed under tension to move the detaining member to detaining position when the controlling member is moved against the action of the spring, and two abutments arranged on the inner side of the door, one for engagement by the locking member to permit the door to open slightly when the detaining member is in locked position but to prevent the door from opening completely and the other for engagement by the detaining member when the door is opened to hold the door in open position.
6. The combination with an elevator shaft having a door opening and a door closing said opening having a normal tendency to move to closed position, of a controlling member controlled by an elevator movable in the shaft, a detaining device for holding the door open, controlled by the controlling member and movable independently thereof, and an abutment on the door for engagement by said detaining device when the door is moved to open position, said abutment having a cam surface which will shift the detaining member to permit the door to be opened after the detaining device has been moved to detaining position, said detaining device being movable manually independently of said controlling member to permit the door to close.

HENRY G. MUTSCHLER.
